Patented Oct. 23, 1917.

UNITED STATES PATENT OFFICE.

ALBERT T. STEWART, OF PEORIA, ILLINOIS.

GAS-BURNING LAMP.

1,243,890.

Specification of Letters Patent. Patented Oct. 23, 1917.

Application filed September 8, 1916, Serial No. 119,085. Renewed April 4, 1917. Serial No. 159,775.

To all whom it may concern:

Be it known that I, ALBERT T. STEWART, citizen of the United States, residing at Peoria, in the county of Peoria and State 5 of Illinois, have invented certain new and useful Improvements in Gas-Burning Lamps; and I do hereby declare that the following is a full, clear, and exact description of the invention, which will enable 10 others skilled in the art to which it appertains to make and use the same.

This invention relates to a lamp for burning gas and particularly to an acetylene lamp adapted for miners' use but also 15 equally well adapted for other purposes.

One of the objects of the invention is to furnish a lamp adapted for producing gas from calcium carbid, or from any other element of a gas forming nature to which a 20 liquid is to be added to form a gas, including what may be termed a "balanced valve" having control of the liquid supplied to such gas forming element.

A further object is to produce a lamp of 25 the type named including a compartment for a gas forming material, calcium carbid for example, a compartment for a liquid such as water, and a separating diaphragm provided with an aperture, part of which 30 constitutes a valve seat, the structure also including in the water compartment a float to which the valve is attached, said float being so proportioned or having such a bulk and consequent buoying power as to practically balance the weight of the valve.

A still further object is to furnish in a lamp of a gas-using type having a compartment for a gas forming material, for example calcium carbid, and a compartment 40 for water separated by a diaphragm, a valve for controlling an aperture in said diaphragm by means of a float having such a buoyancy with regard to the weight of the valve suspended therefrom that the pressure 45 of the gas formed in the compartment for the carbid, when slightly in excess of that required for its ejection through the discharge orifice of the burner, will close said valve and so maintain it and stop the feed 50 of the water to the carbid until such time in the discharge of the gas that the excess pressure of the water has been relieved through said burner, whereupon the valve will open sufficiently by the weight of water 55 thereon to restore working conditions.

Other objects and advantages will ap-

pear in the following specification aided by the accompanying drawing in which letters and other characters of reference correspond.

Figure 1 is a sectional elevation of my improved lamp shown substantially twice the size in lateral and vertical measurement of a lamp of that type customarily used by miners.

Fig. 2 is a plan of a valve.

Fig. 3 is a sectional elevation of a dividing diaphragm and a part of a float shown in Fig. 1, much enlarged; and,

Fig. 4 is a part of said diaphragm and 70 an aperture therein showing certain recesses communicating therewith.

At the outset it may be stated that many attempts have been made to produce a lamp particularly adapted for use in mines which will operate for several hours without attention, so that the workman using the same upon his head-gear will not be required to give any attention thereto during his working hours or "shift." Lamps for this particular purpose using carbide have been constructed in many different ways but the means of conveying the water to the carbide has not produced the best results since it has been found to be very difficult to control 80 the water. The result is that the volume of gas issuing from the jet orifice of the burner is either too great, due to the discharge of too much water upon the gas forming substance, thereby creating too 85 much gas, the flame being often extinguished because of the excessive pressure at the burner opening, or, due to the fact that too little water is allowed to reach the carbide so that the amount of gas created is 90 insufficient to produce a flame.

In addition, all types of lamp with which I am familiar are wasteful in that there is a loss of gas when it exceeds a certain pressure, which finds its way out through the 95 water containing compartment.

My purpose is to construct an acetylene lamp wherein the water is positively controlled in an entirely automatic manner through a substantially balanced valve, as has been stated in the objects, whereby no more water will be permitted to reach the gas forming substance than is actually needed for a required even and steady flow 105 of the illuminant during the entire time of operation of the lamp and without waste of said gas forming substance.

In the drawing A represents a receptacle for the carbide or other gas forming substance which is preferably constricted at its upper end forming a neck B interiorly 5 threaded as shown at C. D is an inverted cup-shaped member part of which constitutes a dividing diaphragm E between the said receptacle A and a second receptacle F for water to be described presently.

10 The said cup-shaped member, which I shall term a diaphragm, is provided substantially midway its height with an extended annular flange G, the portions above and below said flange being threaded at each 15 side, one of said portions thus threaded engaging the threaded neck of the said receptacle A. There is preferably interposed between the flange and the neck of the receptacle A a gasket H to provide a gas tight 20 connection between the described parts.

15 The water receptacle F previously mentioned may be of any approved form of outline preferably having a neck F' having practically vertical walls which in use will 25 contain a column of water. This neck has threaded engagement with the other threaded portion above the flange G and a gasket J corresponding to H is employed to form a water-tight joint. Substantially centrally disposed in the diaphragm E is an aperture K for the reception of a valve to be described, there being a valve seat L on the lower surface of said diaphragm at said 30 aperture facing the compartment A. In the upper surface of the diaphragm and communicating with said aperture K is a series 35 of slits M the purpose of which will be made apparent herein.

40 The previously mentioned valve includes a stem N constructed in the form of a cross or any other convenient form whereby, while permitting the passage of water through the said aperture K in which it lies, said stem will snugly fit said aperture and yet have 45 free endwise movement therein. The valve itself comprises a head O ground to snugly fit the seat L. Loosely attached to the stem N is a float P of any desired form, the ball type being suitable and as a simple manner 50 of connecting the float and valve I may employ a U-shaped wire or staple Q which may pass through an eye, not shown, in the upper end of the valve stem, the terminals of the staple being suitably held in the float. However, 55 other equivalent means of attachment may be employed. Preferably the float is provided with a recess R adapted to receive fine particles of weight-forming material, for instance very fine shot, or the like, this 60 material being indicated at S, the said recess being closed by any suitable means, such as a plug T. Preferably the valve is permitted to have movement within the diaphragm of substantially $\frac{1}{2}$ inch so that but a limited 65 amount of water can pass said valve even

when at its widest opening. This limited movement may be provided for in any desired manner, but as a simple method I make use of the float as the limiting part which in the lowest position or wide-open position of 70 the valve will rest upon the diaphragm 3.

The flange G is provided with a bore U in which tightly fits a tube V the outer end of the latter being closed but provided with a discharge orifice W forming the opening for 75 the jet of gas. The inner end of the tube preferably terminates inward from the inner wall surface of the diaphragm, said inner end lying in a filling of straining material such as finely divided asbestos, cotton X, or 80 the like, which will permit clean gas to pass through it but prevent the passage of particles of carbide or other substance toward or into the tube that might clog the jet orifice W. Preferably there depends from the 85 under face of the diaphragm a tubular portion 2 which separates the described straining material from the place of entrance of the water around the valve, the portions being so constructed as to hold the material 90 X in place. Secured in any suitable manner upon the flange G and surrounding the burner tube B is a reflector 3 of any approved form and of the desired size for the particular lamp to be fitted. The water receptacle F is provided with a capped opening F², the cap F³ for which is furnished with an aperture F⁴ to admit entrance of air so that the water can feed properly past the valve C. 100

4 is a tube snugly fitting into the tubular portion 2 and extending to the bottom of the receptacle A, its lowermost portion being perforated as at 5. The purpose of the tube 4 is to conduct the water from the valve to 105 the interior of the carbide rather than upon the top of the same, it being preferable to have the perforations 5 sufficiently low down that the required amount of carbide will cover them when the lamp is first charged 110 for operation.

By this means the top of the carbide will not become crusted and thus prevent free exit of the gas formed in its interior. In other words, by carrying the water into the 115 mass of carbide the gas formed inside it will have free exit to and through the drier portions above.

It often happens that the incrustation at the top of the carbide prevents the gas readily passing through it from below until such time that sufficient of the gas is created to blow through and when this results a greater pressure is produced at the burner than can be accommodated, producing a flame of variable intensity which disadvantage is sought to be overcome by the structure described. It is not new to deliver water to the interior of the carbide but such devices as deliver the water in a similar manner place the outlet 120 125 130

for the water down inside the carbid so that that material in slackening stops the outlet for the water, requiring the valve also placed at that point, to be opened and closed in order 5 to free the opening by pushing the material out.

My device differs from such a method in that the delivery opening for the water is far removed from the carbid, substantially 10 as described and shown, so that it can never become clogged thereby.

The advantage of being able to vary the buoying action of the float is that in assembling the lamps where valves may differ in 15 weight from one another, the floats therefor may be exactly adjusted for proper working conditions by the removal or addition of a particle of the weight-forming material.

Again, if the material of which the float is 20 made is more or less absorbent and should become slightly "waterlogged," a particle of the weight-forming material may be removed to restore proper working conditions.

The manipulation and operation of the 25 lamp is as follows:—

The receptacle A is provided with the necessary carbid after removing the cupped member D. The removal of the cap F³ from the water receptacle admits of supplying the 30 required amount of water to the latter to raise the float slightly from the position shown in Fig. 1 without closing the valve. The water now passes the valve and upon entering the compartment A gas is formed. 35 When a sufficient amount of gas is created it issues at the burner opening W after passing through the straining material X. The amount of water allowed to pass the valves is sufficient to generate enough gas to provide 40 a flame of the proper intensity, but if for any reason too much gas be generated the pressure at once closes the valve C upon its seat until sufficiently relieved to permit said valve to open by the weight of the water 45 upon it restoring the proper working conditions; the jet or flame being thus kept practically uniform in size.

When the water has fallen during the 50 operation of the lamp to about the level shown in the drawing the amount of carbid with which the lamp is charged has been about exhausted and the float is no longer balanced, sufficient water lacking for that purpose. Thereupon said float drops upon 55 the diaphragm, the valve being then at its full opening and the water that can then flow into the receptacle A does no harm since it falls upon the exhausted carbid.

In order to permit the water to pass out 60 the slits M are furnished in the diaphragm. These slits extend outward from the point of contact of the float on the diaphragm so that said float cannot interfere with the flow of water.

65 The balanced valve, which I believe to be

new, results in a very positive operation of the lamp and steady working of the same.

It is observed that the lamp is quite simple in its appointments and can be readily taken apart and cleaned and restored to condition 70 for use in a very few moments.

I do not wish to be understood as confining myself to the exact arrangement of parts described and shown since I may slightly alter the construction of the lamp and any 75 of its parts required for its operation without departing from the spirit and intent of the invention or the meaning of the claims.

Having thus described my invention, I 80 claim:—

1. In a lamp of the character described utilizing two gas forming elements, one of them being a liquid, said lamp including a compartment for each element, the combination with a diaphragm separating the compartments and provided with an aperture, of a float in the compartment for the liquid, a valve attached to it for closing the aperture, the lifting action of the float being substantially equal to the weight of the valve, 90 the latter being opened by the weight of water thereon in said liquid compartment and adapted to close by the pressure of gas against it.

2. In a lamp of the character described 95 utilizing two gas forming elements, one of them being a liquid, said lamp including a compartment for each element, the combination with a diaphragm separating the compartments and provided with an aperture through which the water flows from one into the other compartment, of a float in the liquid compartment, a valve in the other or gas forming compartment for closing the aperture and connected with the float, the 100 lifting action of the latter being substantially equal to the weight of the valve, the latter being opened by the weight of water thereon in said liquid compartment to permit the liquid to pass to the said gas forming compartment, said valve being closed upon the aperture by an excess of gas created in the last named compartment to stop the 105 flow of said liquid.

3. In a lamp of the character described 115 including in its construction a compartment for each of two gas forming elements, one of the elements being a liquid, the combination of a diaphragm separating the compartments provided with an aperture, a 120 valve to close the aperture, and a float in the liquid compartment attached to the valve, said float having a buoyancy substantially equal in lifting power to the weight of the valve, the valve adapted to open by the 125 weight of the water thereon and adapted to seat and close the aperture due to pressure of gas thereon.

4. A lamp of the character described including in its construction a float chamber 130

having an aperture in its wall for the discharge of fluid from said chamber, a valve to seat upon the wall in control of the aperture, and a float operatively connected to 5 the valve having a buoyancy sufficient to partially lift said valve.

5. A lamp of the character described including in its construction a float chamber having an aperture in its lower wall for the 10 discharge of fluid from said chamber, a valve arranged to close upon the aperture on the outer surface of said wall, and a float operably connected to said valve and having a lifting pull slightly less than the weight 15 of the valve which it controls.

6. A lamp including in its construction two compartments separated by a diaphragm, there being an aperture in said diaphragm, a valve at one side of said diaphragm in 20 control of the aperture, and a float at the other side of said diaphragm operatively in control of the valve.

7. A lamp of the character described including in its construction a float chamber 25 having a discharge aperture in its wall for fluid in said chamber, and a substantially balanced float-valve in control of said aperture.

8. A lamp of the character described including in its construction a float chamber 30 having a discharge aperture in its bottom, and a float-valve in control of said aperture, the weight of the valve being substantially equal to the lifting power of its float.

35 9. In a lamp of the character described having a compartment for a substance from which to form an illuminant, a compartment for water, a diaphragm separating the compartments, the same including an aperture for the discharge of water therethrough upon the described substance, a valve for closing the aperture from within the first named compartment, and a float within the second named compartment operably connected to the valve, the weight of the latter being slightly greater than the lifting power of the float.

40 10. In a lamp of the character described employing gas forming elements, each in a 50 separate compartment, one of which is a liquid, a diaphragm provided with an aperture, the diaphragm separating the compartments for the two elements, a valve to close the aperture outside the liquid compartment, and a float attached to the valve, the lifting power of the float being substantially equal to the weight of the valve, the valve adapted to be partially opened by the weight of the liquid thereon in opposition to the said lifting power of said float.

45 11. In a lamp of the character described including a compartment for each of two gas producing elements, one of which is a liquid, a diaphragm separating the compartments having an aperture therein including

a valve seat at that side of the diaphragm lying outside the compartment for the liquid, a valve including a stem extending into the aperture, and a float within the liquid compartment attached to the stem, the buoyant action of the float being substantially equal to the weight of the valve, the weight of the latter with the water resting thereon adapted to partially offset the said buoyant action of the float; said valve adapted to be closed 75 upon its seat against the liquid by pressure of gas formed in the compartment in which the valve lies.

12. A lamp of the character described including in its construction a compartment 80 for each of two gas forming elements, one of the elements being a liquid, a separating diaphragm for the compartments having an aperture through which the latter communicate, a valve to close the aperture, and a 85 float in the compartment for the liquid, the same having operative connection with the valve and arranged and adapted to receive a variable weight.

13. A lamp of the character described including in its construction a compartment for each of two gas forming elements, one of the elements being a liquid, a separating diaphragm for the compartments having an 90 aperture through which the latter communicate, a valve to close the aperture, and a float operatively connected to the valve, the same being variable in its buoyant or lifting power.

14. A lamp of the character described including in its construction a compartment for each of two gas forming elements, one of the elements being a liquid, a separating diaphragm for the compartments having an 95 aperture through which the latter communicate, a valve to close the aperture, a float operatively connected to the valve, and means to vary the lifting power or buoyancy of said float.

15. In a lamp of the character described 100 including a compartment for each of two gas forming elements, one of them being a liquid, of a diaphragm separating the compartments having an aperture through which 105 said compartments can communicate, a valve to control the aperture situated at one side of the diaphragm, and a float situated in the compartment for the liquid at the other side of the diaphragm and attached to the valve, the lifting power of the float substantially 110 equaling the weight of the valve, there being a burner opening in said diaphragm between the compartments.

16. A lamp of the character described including a compartment for each of two gas 115 forming elements, one of them being a liquid, a separating diaphragm for the compartments in the form of a shell with which the walls of both compartments engage, said diaphragm being separable from both said 120

130

compartments and having an aperture therethrough for the passage of liquid from one compartment into the other, the diaphragm including a tubular part surrounding the aperture and having an open free end, a straining material lying between the said tubular part and the walls of the diaphragm, a burner tube extending through the said wall and terminating within the said material, a valve to control the aperture in the diaphragm at one side of the latter, and a float operatively connected to the valve and lying at the other side of the diaphragm, the lifting power of the float being substantially equal to the weight of the valve, the latter adapted to be opened by the weight of water thereon and adapted to be closed by the pressure of gas in excess of that required to produce a flame of a given size at the opening of the burner tube.

17. A lamp of the character described including in its construction two open-end receptacles, a diaphragm interposed between and connecting the receptacles tightly closing their said open ends and separable from each, there being an aperture in said diaphragm connecting the cavities of the receptacles, there also being an opening in said diaphragm constituting a passage leading outside the lamp, and a substantially balanced float-valve in control of the said aperture.

18. A lamp of the character described including in its construction two open end receptacles, a diaphragm interposed between and connecting said receptacle tightly clos-

ing their said open ends and separable from each, there being an aperture through said diaphragm connecting the cavities of the receptacles, a valve at one side of the diaphragm adapted to close the aperture including a float at the other side of said diaphragm, there being a passage in said diaphragm leading outside the lamp.

19. A lamp of the character described including in its construction a float chamber for containing water having a discharge aperture in its wall for the water, a valve in control of said aperture, a receptacle for a gas-forming material disposed below the aperture, and a conductor for receiving the water from the aperture and conducting it from the said aperture to near the bottom of said receptacle.

20. A lamp of the character described including in its construction two receptacles separated by a diaphragm provided with an aperture, each receptacle adapted for containing a gas-forming element, one of them being water, a valve in control of the aperture, the same being spaced from that portion of the receptacle which contains the other gas-forming element, and a conductor for water extending from the valve and aperture to near the bottom of the last named receptacle.

In testimony whereof I affix my signature, in presence of two witnesses.

ALBERT T. STEWART.
